UNITED STATES PATENT OFFICE.

EDWARD L. DUNN, OF THE UNITED STATES MARINE CORPS.

TYPE-WRITER PLATEN-ROLL-SHIFTING MEANS.

1,252,416.

Specification of Letters Patent.

Patented Jan. 8, 1918.

Application filed October 14, 1916. Serial No. 125,859.

To all whom it may concern:

Be it known that I, EDWARD L. DUNN, a citizen of the United States, and a member of the United States Marine Corps, have invented certain new and useful Improvements in a Type-Writer Platen-Roll-Shifting Means, of which the following is a specification.

This invention relates to typewriter shifting mechanism, and more particularly to means adapted to be attached to the platen roller of a typewriter for shifting the same.

One of the main objects of the invention is to provide a mechanism of simple construction and operation which can be quickly and easily attached to the platen roller of a typewriter of standard construction.

A further object is to provide a mechanism which can be adjusted so as to vary the spacing or column at the left-hand side of the sheet which is being written upon.

A still further object is to provide a mechanism of the character described in which the spacing may be adjusted as desired.

Further objects will appear from the detail description.

In the drawings:

Figure 1 is a side front view of the invention as applied,

Fig. 2 is a longitudinal vertical sectional view taken through the shifting mechanism,

Fig. 3 is a section on the line 3—3 of Fig. 1,

Fig. 4 is a section on the line 4—4 of Fig. 1,

Fig. 5 is a section on the line 5—5 of Fig. 1,

Fig. 6 is a detail perspective view of the latch head,

Fig. 7 is a detail of the adjusting rod for limiting the longitudinal movement of the shifting rod,

Fig. 8 is a front view of the reel casing,

Fig. 9 is a section on the line 9—9 of Fig. 8,

Fig. 10 is a transverse vertical sectional view through the reel and the reel casing,

Fig. 11 is a transverse section through the rack bar and the guide casing therefor; and

Fig. 12 is a detail of the mounting of the reel shaft.

The numeral 1 designates the platen roller of a typewriter which is mounted on a carriage slideable on the typewriter frame, in the usual manner. This roller is mounted

on a shaft 2 which is provided at each end

with the usual hand-knob 3 secured thereto. In applying my invention, I mount an adjusting rod 4 in longitudinal alinement with the shaft 2 of the platen roller. On the inner end of this rod is secured a disk 5 which is mounted in a recess 6 in a slidable block 7. A sleeve 8 is secured about the block 7 and releasably fastened to the hand-knob 3 by means of set-screws 9 threaded through the sleeve and into recesses in the knob. A heavy disk 10 is secured on the rod 4 in spaced relation to the block 7. This disk is recessed to slidably receive a latch-head 11 which is normally held outward from the disk by a coil-spring 12 mounted about the stem of the latch-head and seated in the recess in the disk. This latch-head has its outer end beveled and is adapted to engage into a series of recesses or notches 13 in the outer face of the block 7. These notches are arranged concentric with the shifting rod and are so beveled or inclined that the front tapered end of the latch-head 11 will engage therewith so as to cause rotation of the block 7 in the direction indicated by the arrow in Fig. 1 of the drawings, when the shifting rod is rotated. The bottom of these notches are inclined upwardly in the direction opposite to that in which the block 7 is rotated, and the beveled surface 11^a of the inner beveled end of the latch-head is similarly inclined. By this construction, the shaft 4 is free to rotate in one direction independently of the platen roller shaft 2. To facilitate this free rotation of the rod, the block 7 is provided with a groove in the bottom of the recess 6 concentric with the rod 4. This groove is adapted to receive balls 14 which are confined in the groove by the disk 5. This provides a ball-bearing for the end of the shifting rod and permits easy rotation of the same.

A guide-head 15 is mounted on the adjusting rod 4 beyond the disk 10. A spring-pressed detent 16 is mounted in a recess in the inner end of this guide-head and is held in depressed position by a coil-spring 17 mounted about the shank 18 formed integral with the detent. This shank projects through an annular shoulder 19 integrally connected with the head and is provided, on its upper end, with a gripping head 20. By this means the detent may be easily lifted into inoperative position so as to disconnect the head from the rod. The detent 16 engages with a series of rectangular recesses

- 21 formed in the upper part of the rod 4. By means of the head 15 and the recesses 21 the head 15 may be secured in longitudinal adjustment on the shifting rod.
- 5 An upright 22 is adapted to be secured to a typewriter table 23 by means of a clamp 24, or in any other suitable manner. This upright is provided with an approximately circular guide-casing 25 at its upper end.
- 10 This guide-casing is concentric with the shifting rod 4. A grooved pulley 26 is rotatably mounted on a transverse shaft 27 secured across the guide-casing 25 near its lower end. This pulley is adapted to receive the rod 4. A bracket 28 is secured to a cover 29 secured over the outer side of the upright 22 and casing 25. This bracket is formed with an integral concaved cross-bar 30 at its lower end adapted to fit snugly about the upper portion of the rod 4, so as to confine the rod between the same and the pulley 26. By this means the shifting rod is held in proper adjustment so as to be easily movable axially.
- 15 The guide casing 25 is provided in its inner face, with a plurality of spaced approximately helical grooves 31. The inner end of each groove is flared as at 31^a, so as to readily receive the tapered outer end of a corresponding rib 32 projecting from the periphery of the guide-head 15 and formed integral therewith. These grooves and ribs are so related that when the head is moved into the casing, the grooves will cause the 35 head to be rotated downwardly and rearwardly so as to rotate the rod 4, and consequently the platen roller 1 in the usual direction so as to move the paper in the typewriter up the distance of one space.
- 20 Obviously, by varying the distance which the guide-head is moved into the casing, the amount of rotation of the shifting rod, and consequently the spacing, may be adjusted.
- 25 The pulley 26 is provided with a second smaller groove 33. This small groove is adapted to receive a cable 34, the upper end of which is secured to the outer face of the guide-head 15, near the center thereof, as at 35. The cable 34 passes over a second pulley 36 rotatably supported between the arms 37 projecting downwardly from the cover 29, and is wound about a drum or reel 38 which is keyed on a shaft 39 rotatably mounted on ball-bearings 40 in the side walls of the sheet metal reel casing 41. A pinion 42 is keyed on the shaft 39 adjacent the reel 38 and meshes with a rack-bar 43. This rack-bar is provided with lateral grooves which receive the inwardly directed U-guide members 44 formed integral with the guide-casing 45. This casing 45 is formed of sheet metal and is rigidly secured through the upper section 41^a of the reel casing 41 parallel with and adjacent the inner face of the reel 38. The rack-bar 43 is provided at its lower end, with a rectangularly disposed pedal 46 which projects through a vertical slot 47 formed in the front of the casing 41. By depressing the rack-bar 43 by means of the pedal 46, the reel 38 will be rotated so as to wind the cable 34 thereon, thus moving the guide-head 15 into the guide-casing 25. For this purpose, the casing 41, and the elements mounted therein are adapted to be secured to the floor beneath the table 23 with the pedal 46 in convenient reach of the operator's foot. A set-screw 47 is threaded through the pedal 46 and adapted to contact with the plate 48 secured to the lower end of the casing 41 at the front thereof. By adjusting this set-screw, the downward movement of the pedal 46, and consequently of the rack-bar 43, may be limited to a certain extent so as to vary the amount of rotation of the cable reel 38.
- 30 By limiting the longitudinal or axial movement of the shifting rod 4, the space or column at the left-hand side of the sheet being written upon may be varied. For this purpose a graduated limiting rod 49 is slidably mounted through the upright 22, adjacent the guide-casing 25. This rod is provided with a plurality of equally spaced notches 50. These notches are adapted to receive inwardly projecting arms 51 formed integral with a spring 52 secured to the standard 22. These arms engage into two of the recesses 50 so as to secure the limiting rod in longitudinal adjustment. When it is desired to adjust the rod, it is only necessary to turn it through a half rotation so as to present the smooth side of the rod to the inner ends of the arms 51. For this purpose the rod is provided on its outer end with a knurled head 53. By turning the rod 100 as described, it may be adjusted longitudinally, after which it is turned back so as to bring the arms 51 into engagement with two of the notches 50, thus locking the rod in adjustment.
- 35 The rod 49 is so positioned as to engage the outer face of the annular shoulder 19 of the guide-head 15. By this means the axial movement of the shifting rod 4, and consequently of the platen roller, may be varied. This provides simple and efficient means for varying the spacing or column at the left-hand side of the sheet of paper which is being written upon.
- 40 When the limiting rod 49 is adjusted, it is also necessary to adjust the guide-head 15 so as not to vary the line spacing. For this purpose the recesses 21 of the shifting rod 4 and the notches 50 of the limiting rod 49 are spaced correspondingly. On referring to Fig. 2 of the drawings, it will be evident that, if the limiting rod 49 were moved outward one space, and the guide-head 15 were not moved inward a corresponding distance, the spacing would be greater than for the 105 110 115 120 125 130

adjustment shown in this figure. By moving the limiting rod out one space, the outward movement of the shifting rod 4, and consequently the head 15 would be increased 5 a corresponding distance, so that the head would move a greater distance into the guide-casing 25 and would, as a result, be rotated through a greater distance. By adjusting the head one space to the left for 10 every space that the limiting rod 49 is adjusted to the right, and vice versa, the distance which the head will be moved into the guide-casing 25 will remain constant so as not to vary the line spacing. On the other 15 hand, by varying the adjustment of the head relatively to the limiting rod the distance which the head will move into the guide-casing may be varied so as to vary the line spacing as desired.

20 When it is desired to vary the amount of cable which is wound upon the reel 38, so as to take up slack or for any other reason, the top 41^a of the casing 41 is removed for this purpose. The top 41^a and the body of the 25 casing are provided with outwardly directed flanges 41^b provided with alined perforations adapted to receive securing screws 53. By removing these screws the top 41^a may be lifted vertically so as to remove the 30 guide-casing 45 from about the rack-bar 43. This permits the rack-bar to be moved out of engagement with the pinion 42 so that the reel 38 may be rotated so as to wind the desired amount of cable onto the reel, after 35 which the rack-bar is moved into engagement with the pinion and the top 41^a and guide-casing 45 are again secured in position.

The guide-head 15, after it has been 40 moved into the guide-casing 25 will be moved out of the casing as the shifting rod 4 is moved longitudinally in accordance with the longitudinal movement of the platen roller carriage which will be moved along 45 the type-writer frame during the operation of the typewriter in the usual manner. When the typewriter carriage is moved to its extreme position at the left-hand side of the machine the head 15 will be in its initial 50 position relatively to the guide-casing 25. By pressing on the pedal 46 the rod 4 and guide-head 15 together with the platen roller and the typewriter carriage, will be again shifted to the extreme right-hand position, and the platen roller will be simultaneously rotated so as to move the sheet of 55 paper up one space. This operation will be repeated after each line which is typewritten upon the sheet of paper in the typewriting machine. Of course, during the inward movement of the shifting rod 4, the rod will 60 rotate freely and independently of the platen roller, as previously described.

I have described my mechanism as used 65 in connection with a typewriter of standard

construction in which the key-board of the typewriting machine is shifted when changing from first case to second case letters or numerals, or the like. However, it will be evident that certain other variations may be 70 made in the construction and arrangement, of the various parts of my invention without departing from the field and scope of the same and I intend to include all such variations as fall within the scope of the appended 75 claims of this application in which a preferred form only of my invention is disclosed.

What I claim is:

1. In a mechanism of the character described, the combination of a platen roller, a longitudinally movable shifting rod secured to one end of the roller so as to have free rotary movement in one direction, means for moving the rod longitudinally and 80 for simultaneously rotating it, and connections between the rod and the roller for rotating the roller in one direction when the rod is rotated.

2. In a mechanism of the character described, the combination of a platen roller, a longitudinally movable rod secured to one end of said roller so as to be rotatable independently thereof in one direction, means for moving the rod longitudinally and for causing 90 rotation thereof, and connections between the rod and the roller for rotating the roller when the rod is rotated in the other direction.

3. In a mechanism of the character described, the combination of a platen roller, a longitudinally movable rod secured in one end of said roller so as to be rotatable independently thereof in one direction, means for moving the rod longitudinally and for 100 causing rotation thereof, connections between the rod and the roller for rotating the roller when the rod is rotated in the other direction, and means for positively limiting the longitudinal movement of the rod.

4. In a machine of the character described, the combination of a platen roller, a longitudinally movable rod having one end secured to the roller and being rotatable independently thereof in one direction, means 110 for operatively connecting the rod to the roller during its rotation in the other direction, and means for moving the rod longitudinally and for simultaneously causing rotation of the rod in a direction to rotate the 115 platen roller.

5. In a machine of the character described, the combination of a platen roller, a longitudinally movable rod having one end secured to the roller and being rotatable independently thereof in one direction, means 125 for operatively connecting the rod to the roller during its rotation in the other direction, means for moving the rod longitudinally and for simultaneously causing rota-

tion of the rod in a direction to rotate the platen roller, and adjustable means for varying the longitudinal movement of the rod.

6. In a mechanism of the character described, the combination of a platen roller, a guide casing provided with helical guide grooves, a rod slidably mounted through the casing in longitudinal alinement with the roller and having one end secured to the roller so as to be rotatable independently thereof in one direction, connections between the rod and the roller for causing rotation of the roller when the rod is rotated in the other direction adapted to permit free rotation of the rod in the first direction, a head mounted on the rod and secured against rotary movement relatively thereto, said head being provided with members adapted to engage the grooves in the casing so as to cause rotation of the head when the head is moved into the casing, and means for moving said rod longitudinally through the casing.

7. In a mechanism of the character described, the combination of a platen roller, a guide casing provided with helical guide grooves, a rod slidably mounted through the casing in longitudinal alinement with the roller and having one end secured thereto so as to be rotated independently of the roller in one direction, connections between the rod and roller for causing rotation of the roller when the rod is rotated in the other direction adapted to permit free rotation of the rod in the first direction, a head mounted on the rod

and adjustable longitudinally of the same, 35 said head being adapted to fit into the guide casing and provided with members adapted to engage the grooves thereof so as to cause rotation of the head when it is moved into the casing, and means for moving the said 40 rod through the casing.

8. In a mechanism of the character described, the combination of a platen roller, a guide casing provided with helical guide grooves, a rod slidably mounted through the 45 casing in longitudinal alinement with the roller and having one end secured thereto so as to be rotatable independently of the roller in one direction, connections between the rod and roller for causing rotation of the 50 roller when the rod is rotated in the other direction adapted to permit free rotation of the rod in the first direction, a head mounted on the rod and adjustable longitudinally of the same, said head being adapted to fit 55 into the guide casing and provided with members adapted to engage the grooves thereof so as to cause rotation of the head when it is moved into the casing, means for moving the said rod through the casing, and adjustable means for positively limiting the outward movement of the head.

In testimony whereof I affix my signature in presence of two witnesses.

EDWARD L. DUNN.
